UNITED STATES PATENT OFFICE.

JOHN ELLIS, OF PITTSBURGH, PENNSYLVANIA.

WATER-HEATER.

1,058,370.

Specification of Letters Patent. Patented Feb. 18, 1913.

Application filed April 25, 1912. Serial No. 693,504.

To all whom it may concern:

Be it known that I, JOHN ELLIS, a citizen of the United States, residing at Pittsburgh, in the county of Allegheny and State of Pennsylvania, have invented a new and useful Improvement in Water-Heaters, of which improvement the following is a specification.

My invention relates in particular to the water and gas controlling mechanism of water heaters.

The invention has for its objects; the provision of a single gas controlling valve and mechanism therefor, to take the place of a plurality of gas valves as usually employed; to operate the gas supply valve to permit the gas to flow to the burner by the action of the thermostat, when water is drawn from the heater; and to hold the gas valve to its seat by means of the water valve to prevent the cooling effect of the thermostat opening said gas valve until the hot water faucet is opened to draw water from the heater.

With the above objects in view, the invention consists in certain novel features of construction, and in certain parts, improvements, and combination of parts, as will be hereinafter more particularly described and pointed out in the appended claims.

One embodiment of the invention is illustrated in the accompanying drawings, forming a part of this specification, each detail part of the structure being given and referred to by its individual reference numeral throughout the several views, said views representing the following:

Figure 1 is a side elevation of the gas and water valves and connecting parts, partly in section. Fig. 2 is a plan view thereof, also partly in section. Fig. 2' is an enlarged, partly sectioned, side elevation of the secondary lever of the thermostat mechanism for operating the gas valve, and an inverted plan of the same. Fig. 3 is a side elevation of a heater having my improvement applied thereto. Fig. 4 is a modified form of the water valve and connection to the gas valve.

In detail, the structure shown comprises a casing formed of the two connected parts 1 and 2, the interior chamber being divided but communicating by a valve controlled opening 3, which chamber casing is connected in the gas line, as shown in Fig. 3. The upper chamber portion is provided with a gas-controlling disk valve 4, to engage upon the seat formed about the communicating

opening, which valve has formed on its underside the downwardly extended stem 5 and guides 6, and on its upper side the upwardly extended stem 3' engaging in the guide 7 of the screw cap 8, said valve being provided with a seating spring 9, and said screw cap with a stuffing box 10 and stuffing 11. The lower portion of the chamber casing is connected to a horizontally disposed pipe 12, connected in the water service line, and to the thermostat tube 13 inclosed by said pipe and has arranged therein the thermostat rod 14, which is engaged at one end by the head of the thermostat tube and has its free end projecting slightly into the chamber.

Within the lower portion of the chamber, is seated a horizontally disposed and movable thrust-pin 15, having formed thereon the vertically disposed guide portion 15' and supporting portion 15'', the point of said thrust-pin engaging in a small conical opening formed in the lower face portion of the vertically disposed primary lever 16. This primary lever is supported by a vertically disposed rest 17, by engaging with a transversely disposed knife-edged fulcrum-rib 17', upon the rest, at the V shaped grooved portion extending across its rear, said fulcrum point being located at a point slightly above the axial line of the thrust pin. The lever rest is provided at its upper end with a pair of forwardly disposed lugs 17'', each notched at its rear, and between which the upper rounded end of the primary lever extends, the lower rear portion of said rest being further provided with a transversely disposed fulcrum rib 18, located at a point slightly below the axial line of the thrust pin. Disposed between the lugs of the lever rest, is a horizontally disposed secondary lever 19, provided at its rear with laterally projecting fulcrum lugs 19' engaging in the notched portions of the rest lugs and further engaging, at its under transverse portion 20, with the upper end of the primary lever, the forward end of this secondary lever having a pocket formed therein, within which is arranged a spiral spring 21 and upon which rests a head 22 having a stem 23 provided with a nut 23' for adjusting the head and placing the spring under the desired tension. Within the lower portion of the rear wall of the chamber is arranged a screw plug 24, engaging the rib 18 of the lever rest, and provided with a jam nut 24',

100

adapted to adjust and take up the slack between the primary lever, the thrust pin and the thermostat rod and secure the same in adjusted position. A set screw 26, provided with a jam nut 26', is arranged at the upper rear portion of the chamber for adjusting the upper end of the rest and secondary lever and secure the rest in adjusted position.

Rigidly secured upon the vertically disposed bracket 27 of the gas chamber casing, is the water valve casing 28, having a removable head 29, and provided with a water inlet 30 and a water outlet 31 by which it is connected in the water line leading to the heater. Within this casing forming the water chamber, about the valve seat, is formed a groove 32, communicating with the water inlet, and at the lower end of the seat is formed a similar groove 33, communicating with the water outlet, said water inlet also communicating with the upper end of the chamber by a small leakage port 34. Fitted to travel within this chamber is a piston valve 35, of substantially cup shape, disposed with its head uppermost, and provided with a plurality of spaced ports 36, and a small leakage port 36', formed through its annular wall portion. Extending down through the projecting boss 37 upon the lower end of the chamber casing, and through the stuffing box 38, and cap 39, is a piston rod 40, having a head 40' at its upper end engaging with the piston valve head, about which rod is arranged a spiral spring 41 for returning to and holding the piston in its normal elevated position, and at the same time hold the gas valve upon its seat against any opposing action of the thermostat. As here shown, the mechanism interposed between the two valves for holding the gas valve to its seat, comprising a lever 43 pivotally connected to the bracket 27 by a pivot screw 44, one end of said lever engages a spool bearing 42 on the lower end of the piston rod of the water valve, and the other end thereof engaging a similar spool bearing upon the plunger 46 which extends down through the cap 8 of the gas chamber and engages the stem of the gas valve.

Normally, the gas and water valves, and operating parts, assume the positions indicated at Fig. 1, the operation thereof in practice, being as follows: Opening the hot water service faucet of the heater (not here shown), relieves the pressure of the water upon the underside of the piston valve 35, thus permitting an increased volume of water to enter the upper end of the chamber, by way of the leakage port 34, the pressure of which forces the piston valve to descend sufficient distance to cause the ports 36 thereof to establish communication with the water inlet and permit the water to enter therethrough to and through the piston 65 to the water outlet, and heater coils in the

line to the service faucet, which downward movement of the piston valve depresses the stem 40 and elevates the plunger 46, through the medium of the pivoted connecting lever 43, thus releasing the gas valve 4. Prior to the movement of the water valve, the contraction of the thermostat tube 13 having forced the thermostat rod 14 to move the thrust pin 15, primary lever 16, and secondary lever 19, elevating the free end of the latter into engagement with the gas valve, by which movement of the secondary lever, the spring 21 in the end thereof would have been depressed, as shown in Fig. 1, but upon the downward movement of the water valve 75 the pressure exerted thereby upon the gas valve being thus removed, the said spring 21 expands and overcomes the spring 9, thus raising the gas valve from its seat and permitting the gas to flow to the burner. Upon 80 closing the hot water service faucet, the water gradually leaks into the piston, by way of the port 36', the pressure of which, assisted by the spring 41, returns the piston to its normal elevated position. As the piston valve returns to its normal position, the lever 43 causes the plunger 46 to descend and reengage with the stem of the gas valve, holding said gas valve to its seat, the pressure exerted by the water valve upon the gas 95 valve being sufficient to overcome the spring 21, of the secondary lever, when the temperature of the water is low.

In Fig. 4, the modification shown, consists in constructing the water valve chamber casing so as to have the removable head at the water outlet end; inverting the same in axial alinement with the gas valve; fixedly attaching the stem 50 to the piston valve and extending the same down into direct engagement (normally) with the gas valve stem, the spring 51 being suitably held in engagement with the piston and chamber heads. In this modification, the operation would be substantially the same as the preferred form, except that the water valve piston rod releases the gas valve by its upward movement, instead of the downward movement.

Having thus shown and described an operative embodiment of my invention, what I claim, is:

1. In a water heater, the combination of a gas controlling valve, a thermostat mechanism for opening said gas valve, and an automatic water controlling valve provided with a spring adapted to operate on the water valve and also adapted, when said water valve is in its normal position, to exert pressure upon and hold the gas valve 120 in closed position.

2. In a water heater, the combination of a gas controlling valve, a thermostat mechanism for opening said gas valve, means for closing said valve, and an automatic water 125

controlling valve having therein a spring adapted to operate on the water valve and also adapted, when said water valve is in its normal position, to exert pressure upon 5 and hold the gas valve in closed position.

3. In a water heater, the combination of a gas controlling valve, a yieldable thermostat mechanism for opening said gas valve, and an automatic water controlling valve provided with a spring adapted to operate on the water 10 valve and also adapted, when said water valve is in its normal position, to exert pressure upon and hold the gas valve in closed position.

15 4. In a water heater, the combination of a gas controlling valve, a thermostat mechanism for opening said gas valve, an automatic water controlling valve provided with a spring adapted to operate on the water 20 valve, and a pivoted gas-valve-holding lever connected to said water valve, said water valve spring also adapted, when said water valve is in its normal position, to exert pressure upon said lever to hold the gas valve 25 in closed position.

5. In a water heater, the combination of a gas controlling valve, a thermostat mechanism for opening said gas valve, an automatic water controlling valve provided with a spring adapted to operate on said water 30 valve, and a pivoted gas-valve-holding lever connected to said water valve, said water valve spring also adapted, when said water valve is in its normal position, to exert pressure upon said lever to hold the gas valve 35 in closed position, and said thermostat mechanism being yieldable to the pressure of the water valve spring acting upon the gas valve in opposition thereto.

40 6. In a water heater, the combination of a gas controlling valve, a thermostat mechanism for opening the gas valve, an automatic water controlling valve, a rod movable therewith, and a pivoted gas-valve-holding 45 lever positively connected to said rod for holding the gas valve to its seat when said water valve is in its normal position.

7. In a water heater, the combination of a gas controlling valve, a thermostat mechanism for opening the gas valve, an automatic water controlling valve, a rod movable therewith, and a pivoted gas-valve-holding 50 lever positively connected to said rod for holding the gas valve to its seat when said water valve is in its normal position, said thermostat mechanism being yieldable to the pressure of the water valve exerted upon the gas valve in opposition thereto.

60 8. In a water heater, the combination of a gas chamber, a gas controlling valve therein

provided with a seating spring, a thermostat tube connected to said chamber, a thermostat rod inclosed by said tube and projecting into said chamber, means in said 65 chamber operated by the thermostat controlled rod for opening the gas valve, an automatic water valve, a rod operating with said water valve, a pivoted lever operated by said water valve rod and provided with a plunger for holding the gas valve to its 70 seat to prevent the opening of the same by the thermostat mechanism until water is drawn from the heater, and screws extending through the gas chamber for adjusting 75 the thermostat gas valve opening means.

9. In a water heater, the combination of a gas chamber, a gas controlling valve therein provided with a seating spring, a thermostat tube connected to said chamber, a thermostat rod inclosed by said tube and projecting into said chamber, means in said 80 chamber operated upon by the thermostat controlled rod for opening the gas valve, an automatic water controlling valve, a rod 85 operating with said water valve, and a pivoted lever operating with said rod and provided with a plunger for holding the gas valve to the seat to prevent the opening thereof by the thermostat mechanism until 90 water is drawn from the heater, the thermostat gas operating mechanism being yieldable to the pressure exerted by the gas valve holding mechanism.

10. In a water heater, the combination of a gas chamber, a gas controlling valve therein provided with a seating spring, a thermostat tube connected to said chamber, a thermostat rod inclosed by said tube and projecting into said chamber, means in said 100 chamber operated by the thermostat controlled rod for opening the gas valve, an automatic water valve, a rod operating with said water valve, a pivoted lever operating with said water valve rod and provided with a plunger for holding the gas valve to its 105 seat to prevent the opening thereof by the thermostat mechanism until water is drawn from the heater, and screws extending through the gas chamber for adjusting the 110 thermostat gas valve opening means, said thermostat gas valve operating means being yieldable to the pressure exerted on the gas valve by the holding means.

In testimony whereof, I have hereunto 115 signed my name in the presence of two subscribing witnesses.

JOHN ELLIS.
